UNITED STATES PATENT OFFICE.

ALBERT DAY, OF WINSHAM GROVE, LONDON, ENGLAND.

MACHINE FOR MAKING AND FILLING PACKETS.

Application filed April 14, 1924. Serial No. 706,437.

To all whom it may concern:

Be it known that I, ALBERT DAY, a subject of the King of Great Britain, residing at 53 Winsham Grove, in the county of London, England, have invented certain new and useful Improvements in or Relating to Machines for Making and Filling Packets, of which the following is a specification.

This invention relates to machines for making and filling packets, of the kind comprising a folder termed the "fourth folder," having consecutive horizontal and vertical movements, a stationary mould slotted to give passage to the said folder, and a vertically movable funnel having a hollow stem or "former" to which the charge of tea or other material to be packed was delivered while the bag was being made thereon, the operations of making and filling one bag proceeding simultaneously with the operations of closing and ejecting the preceding filled bag.

According to the present improvements the "former" is vertically reciprocable, moving with the said fourth folder, and the slotted mould is stationary and has a movable bottom to allow the folder or other moving part to carry or push a filled packet down to an ejector platform situated at a lower level.

In order that the said invention may be clearly understood and readily carried into effect the same will now be described more fully with reference to the accompanying drawings illustrating the parts of the machine with which the present invention is concerned.

Figure 1 is a front elevation.

Figure 2 is a partial side elevation.

Figure 3 is a plan taken on the line 3—3 in Figure 2.

Figure 4 is a plan taken on the line 4—4 in Figure 2.

Figure 5 is a plan taken on the line 5—5 in Figure 2.

The reference numeral 11 indicates the framework of the machine, in which are secured pillars 250, 251, connected together by a crossbar 259 (Figure 1). In the frame 50 11 are mounted rotary shafts 24 and 136, and stay rods 58, 141, and 217 (Figure 2) are utilized for the support of movable parts of the machine. A rammer 260 (Figure 1) is carried in a bracket 252 adapted to be reciprocated on the pillars 250, 251 by

cranks 255, 256 on the shaft 136, which cranks are connected by rods 257, 258 with the said bracket 252.

The "former" A is carried in a bracket a' vertically reciprocated on the pillars 250, 251, by a rod a^2 which receives its motion from a lever a^3 pivoted on the stay rod 141 and carrying a bowl a^4 engaging a cam a^5 on the rotary shaft 136.

The mould B is affixed to the machine frame by a bracket b' , and its wall at b^2 (Figures 2 and 3) is slotted to give passage to the "fourth folder." Its floor or bottom plate b^3 which has a T shaped slot (see Figure 4) is periodically withdrawn and returned to the position shown by means of a reciprocating rod b^4 actuated by a lever b^5 pivoted on the stay rod 141, this lever carrying a bowl b^6 engaging a cam b^7 on the rotary shaft 136. Instead of having a simple backward and forward movement, the mould bottom plate may be pivoted and swung to one side when its absence from the mould is required, or it may be made in two halves arranged to slide apart in diametrically opposite directions, or the two halves may be separately pivoted and arranged to open out or swing on their pivots away from each other.

The fourth folder is T shaped in plan 35 comprising a shank C having upper and lower lateral extensions c' (Figure 3) and c^2 (Figures 1 and 2) which provide a broad front at each of the operative parts of the folder, namely the upper part which completes the folding of the bottom of the filled bag under the "former" and the lower part which completes the folding of the top of the packet in the mould, on the forward stroke of the folder. This forward stroke is accomplished by a two-armed lever 213 pivoted on the stay rod 58 and carrying a bowl 210 in contact with a cam 207 on the rotary shaft 24, a spring 212 holding the bowl against the cam, and the longer arm 90 of the lever 213 being connected with the shank C of the folder by a slotted guide link 214. The folder shank C has a downward extension 218 connected with a three-armed lever 216 pivoted on the stay rod 217 and carrying a bowl 220 engaging a cam 208 on the rotary shaft 24; a spring 221 holds the bowl 220 against its cam. This cam 208 thus effects a downward stroke of 95 the folder, this being timed to occur imme- 100 diately after the forward stroke of the folder, 105 and the cam 208 is so timed to occur imme- 110 diately before the return stroke of the folder.

diately after the last folds have been made by the forward stroke of the folder, and to coincide with the downward stroke of the "former" obtained by the action of the 5 cam a^5 as aforesaid.

A lower blade or foot D may be secured to the shank C of the folder as shown in Figures 2 and 4, the said blade D therefore partaking in the movements of the folder.

10 Alternatively this blade D may be moved by separate mechanism, but it must follow the movements of the folder to perform the functions hereinafter described.

The ejector platform E (Figures 2 and 15 5) is slotted at e' to allow the blade D to pass through it and travel below the path of the ejector F when the latter is advanced to push a packet off the platform E into the ejector trough e^2 .

20 When by the lifting of the rammer 260 the charge of tea or other material has been delivered into the "former" A so as to rest on the first fold of the bottom of the bag, the second and third folds being then made, 25 the fourth folder advances from the position shown in Figure 2 so that the part c' thereof completes the folding of the part of the bag bottom projecting below the "former" A and the part c^2 completes the folding of 30 the top of the packet in the mould B, the blade D simultaneously advancing into the slot in the mould bottom plate b^3 under the packet. Ramming of the charge in the bag may be performed before, during, or after 35 the transfer of the filled bag to the mould, which transfer is effected by the "former," folder, and blade D descending together, while the plate b^3 is withdrawn to allow the completed packet from the mould to be carried down between the part c^2 and blade D. 40 The plate b^3 then advances over the top of the part c^2 with its slotted portion passing at each side of the narrow central part C of the folder, so that the said plate b^3 is ready 45 to support and control the bottom of the filled bag when the upper part c' of the folder has passed through the T-shaped slot in the plate b^3 , at which time the blade D has also passed through the slot e' in the 50 ejector platform E, leaving the completed packet on the ejector platform. The folder and blade D are then drawn back clear of the mould and packet, and rise to repeat 55 their forward stroke, while the ejector F pushes the packet off the platform E into the ejector trough e^2 , and the "former" rises again to receive the next wrapper for making another bag, the rammer remaining in the "former" until the rammer has to be 60 further lifted to admit the next charge.

Alternatively the ejector platform E may be arranged to rise to receive the packet from the mould, and descend with the said packet to the position in which the packet 65 is removed to the trough e^2 .

What I claim and desire to secure by Letters Patent of the United States is:—

1. In a machine for making and filling packets, a vertically reciprocable former, a folder having consecutive horizontal and vertical movements, said vertical movements of said folder synchronizing with the vertical movements of said former, a stationary mould located under said former and vertically slotted to give passage to said folder, 70 said mould having a movable bottom to give passage to a packet, and an ejector platform located below said mould.

2. In a machine for making and filling packets, a vertically reciprocable former, a folder having consecutive horizontal and vertical movements, said vertical movements of said folder synchronizing with the vertical movements of said former, a stationary mould located under said former and vertically slotted to give passage to said folder, 80 said mould having a movable bottom to give passage to a packet, a blade moving in unison with said folder, said blade being adapted to pass under said mould to support said 85 packet, and an ejector platform located below said mould and slotted to give passage to said blade.

3. In a machine for making and filling packets, a vertically reciprocable former, a folder having consecutive horizontal and vertical movements, said vertical movements of said folder synchronizing with the vertical movements of said former, a stationary mould located under said former and vertically slotted to give passage to said folder, 90 said mould having a movable bottom to give passage to a packet, said folder being adapted in its operative horizontal stroke to close simultaneously the last fold of a bag bottom 100 on said former and the last fold of the top of a packet in said mould, a blade moving in unison with said folder and adapted to pass under said mould to support said packet, and an ejector platform slotted to 105 give passage to said blade and adapted to receive said packet when said packet is carried down between said folder and said blade.

4. In a machine for making and filling 115 packets, a vertically reciprocable former, a folder having consecutive horizontal and vertical movements, said vertical movements of said folder synchronizing with the vertical movements of said former, a stationary mould located under said former and vertically slotted to give passage to said folder, 120 said folder having upper and lower portions of T section to engage respectively the bottom of a bag on the former and the top of a packet in the mould, a movable mould bottom having therein a T slot to give passage to said folder, and an ejector platform located below said mould.

5. In a machine for making and filling 125

packets, a vertically reciprocable former, a folder having consecutive horizontal and vertical movements, said vertical movements of said folder synchronizing with the vertical movements of said former, a stationary mould located under said former and vertically slotted to give passage to said folder, said folder having upper and lower portions of T section to engage respectively the bottom of a bag on the former and the top of

a packet in the mould, a blade moving in unison with said folder and adapted to pass under said mould to support said packet, a movable mould bottom slotted to give passage to said folder and blade, and an ejector ¹⁵ platform located below said mould, said platform being slotted to give passage to said blade.

ALBERT DAY.
